ASSIGNORS, BY MESNE ASSIGNMENTS, TO THE G. W. DULANY TRUST, OF CHICAGO,
ILLINOIS, A COMMON-LAW TRUST

HEATER

Application filed February 23, 1929. Serial No. 342,200.

The present invention relates to improvements in heaters or steam generators.

The primary object of the present invention resides in the provision of a new and improved steam generator or heater which is relatively simple, inexpensive and compact in construction, and for a given capacity requires a relatively small floor space, which is highly efficient and safe in operation, and which may be readily assembled and disassembled.

More specific objects reside in the provision of a novel steam generator or heater, comprising a water space and tortuous circulating tubes, in which a long flue gas passage is provided, in which a counterflow between the flue gases and the medium in the tubes is set up, in which means is provided for creating a substantial turbulence of the flue gases, in which the heated walls of the water space are cooled at all times even though the water level is relatively low, and in which the tubes may be readily and quickly removed singly.

Further objects and advantages will become apparent as the description proceeds.

In the accompanying drawings, Figure 1 is a vertical sectional view taken along line 1—1 of Fig. 2 of a generator embodying the features of our invention.

Fig. 2 is a vertical sectional view taken along line 2—2 of Fig. 1.

Fig. 3 is a horizontal sectional view taken along line 3—3 of Fig. 2.

Fig. 4 is a horizontal sectional view taken along line 4—4 of Fig. 2.

Fig. 5 is a horizontal sectional view taken along line 5—5 of Fig. 1.

Fig. 6 is a fragmentary sectional view taken along line 6—6 of Fig. 1.

Fig. 7 is a fragmentary sectional view taken along line 7—7 of Fig. 1.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative con-

structions falling within the spirit and scope of the invention as expressed in the appended claims.

The features of the invention although disclosed in a unit referred to herein as a steam generator are applicable to various heating units, such as a domestic water heater, and it is therefore to be understood that we intend to cover the invention broadly for all uses to which it is adapted.

Referring more specifically to the drawings, the generator or heater constituting the exemplary embodiment of the invention may be of any suitable form, and in the present instance is generally rectangular in shape and disposed vertically. The generator comprises side walls 10 and 11, end walls 12 and 13 and a bottom wall 14. These walls may be made of any suitable material, and may have any suitable form. In the present instance, the side walls 10 and 11 are constructed of sheet metal and are removably secured to the end walls 12 and 13. Mounted on the inside of each of the side walls 10 and 11 is a layer of heat insulating material 15 such as asbestos, preferably in the forms of blocks. The end walls 12 and 13 preferably are cast, and are hollow to provide vertical downflow water passages 16.

Disposed between the lower ends of the end walls 12 and 13 and underlying the side walls 10 and 11 are two suitable mud drums 17. Preferably the mud drums 17 are substantially rectangular in lateral cross section, and are castings. The opposite ends of the mud drums 17 are rigidly secured to the end walls 12 and 13 by means of bolts 18 and to the side walls 10 and 11, and communicate through suitable connections 19 with the lower ends of the water passages 16. Feed water is adapted to be supplied to the mud drums 17 through inlet pipes 20 adapted to be connected to a suitable source of supply (not shown).

The end walls 12 and 13 project a substantial distance above the side walls 10 and 11. Disposed between the projecting upper ends of the end walls 12 and 13 and along the top edges of the side walls 10 and 11 is a suitable hollow head structure 21, provid-

ing a water chamber 22. The side walls are removably secured to the head structure 21. The bottom wall 23 of the head structure is formed with a centrally disposed and downwardly opening dome 24 constituting a combustion space or chamber. The head structure 21 is rigidly secured to the end walls 12 and 13 by means of bolts 25, and the interior thereof communicates at the top and 10 also at opposite sides of the bottom through suitable connections 26 with the passages or legs 16. Preferably, the opposed connections 26 are aligned.

In the top of the chamber 22 is a suitable take-off pipe 27 which preferably is formed with a plurality of small openings 28. The opposite ends of the pipe 27 extend through the upper connections 26 and the side walls 10 and 11. Of the pipe 27, one end is closed 20 by means of a removable plate 29, and the other end is adapted to be connected to a suitable discharge line (not shown). A safety valve (not shown) may be mounted in the top wall of the head structure 21.

Any desired number of suitable burners may be provided in the combustion chamber 24, and these may be arranged in any suitable manner. In the present instance, six burners 32 of standard construction are provided, and three thereof on each side are mounted in integral sleeves 33 in each of the side walls of the head structure and open into the sides of the dome 24. While any suitable fuel may be used, preferably the burners 32 are adapted to burn gas, and to this end are connected to a suitable gas manifold 34 leading from a source of fuel (not shown). A suitable pilot light 35 is mounted in one of the end walls 12 and 13 in position 40 to direct a lighting flame past the ends of the opposed burners 32.

The interior of the generator below the dome 24 constitutes a heating chamber 31. The lower ends of the end walls 12 and 13 are formed with openings 36 communicating with the lower end of the heating chamber 31. Of the openings 36, one is closed by a removable plate 37 and the other is connected to a suitable stack 38.

Disposed in the heating chamber 31 below the dome 24 are a plurality of heating tubes 39. Preferably, the tubes 39 are flat and sinuous in shape, and are arranged side by side in closely spaced relation parallel to the end walls 12 and 13. The lower ends of the tubes 39 are connected alternately to the mud drums 17 with which they communicate through ports 40, and are removably secured in position by means of suitable clamp members 41. Likewise, the upper ends of the tubes 39 are connected alternately to opposite sides of the bottom wall 23 of the head structure 21 to which they are removably secured by means of clamp members 42. Most of the tubes 39 communicate through ports 43

with the bottom of the water chamber 22. Certain of the tubes 39 at spaced intervals are connected to extension pipes 44 extending upwardly into the water chamber 22 and discharging to hollow fittings 45 preferably formed integral with the side walls 70 of the head structure 21. The outer walls of the fittings 45 are apertured, and normally are closed by removable plugs 46 which can be removed to give access thereto. Projecting horizontally from the fittings 45 75 over the central area of the top wall of the dome 24 are a plurality of discharge members 47 preferably in the form of spouts.

A plurality of transverse baffles 48 laterally inclined from the horizontal are disposed between the bends of the tubes 39 and serve to direct the products of combustion from the burners 32 along the course of the tubes, thereby providing a long tortuous flue gas passage. The baffles 48 preferably are in the form of plates, the end edges of which are slidably supported in suitable notches 49 in the end walls 12 and 13. The outer end of the baffles 48 are removably held between a plurality of vertical wall sections 50 disposed closely along the side walls 10 and 11. The upper wall sections 50 are inclined inwardly toward the dome 24.

To create turbulence in the gas flow along the baffles 48, the baffles directly over the tubes 39 are provided at spaced points with a plurality of depending vanes 51. Each vane presents a gradually inclined or curved deflecting surface 52 to the flowing gases.

In operation, feed water is supplied to the mud drums 17, and from there passes upwardly through heating tubes 39. The water or steam-water mixture from the upper ends of the tubes 39 is discharged into the bottom of the water chamber 22. Water in the legs or passages 16 moves downwardly by convection, and joins the incoming feed water passing to the heating tubes 39. Steam is withdrawn as required from the take-off pipe 27.

It will be evident that a relatively long flue gas passage is provided, and that a counterflow between the medium in the tubes 39 and the flue gases is set up. The vanes 51 create a violent turbulence in the flue gases in the course of their passages along the tubes. As a result, a relatively high efficiency is obtained. It will be noted that the walls of the combustion chamber 31 are either water cooled or insulated, thereby preventing the loss of heat through radiation from the outer surfaces.

The medium from certain of the heating tubes 39 is discharged directly onto the top wall of the dome 24, thereby serving to keep the latter cool regardless of the water level in the chamber 22. Thus, if the water level were substantially below the top of the dome 125

22, water still would be spilled onto the top wall to prevent overheating.

The tubes 39 and the baffles 48 can be removed singly and with facility. This may be accomplished by removing one or both of the side walls 10 and 11 to give access to the interior of the chamber 31. The baffles 48 may then be drawn out along the notches 49. To remove any one tube 39, the clamp members 41 and 42 are released, and the ends of the tube are then flexed slightly whereupon the entire tube can be freely removed.

In general, the construction is simple, inexpensive and compact, and for a given capacity but a very small space is required.

We claim as our invention:

1. A heater comprising, in combination, an upright heating chamber, a head structure closing the top of said heating chamber, the interior of said structure constituting a water chamber, a part of the bottom wall of said head structure being raised to define a combustion chamber, a plurality of burners opening to said combustion chamber, a flue gas outlet at the lower end of said heating chamber, a series of heating tubes disposed in said heating chamber and opening into said water chamber, certain of said tubes being arranged to discharge onto the raised portion 25 of the bottom wall of said head structure and means for supplying water to said tubes.

2. A heater comprising, in combination, a heating chamber having opposed side walls and end walls, two opposed walls being hollow to form water legs and extending substantially above the other walls, a hollow head casing secured between said last mentioned walls and over said other walls and communicating with the upper ends of said 35 water legs, a plurality of generally vertical tortuous heating tubes disposed in said chamber, the upper ends of said tubes communicating with said head casing, means for supplying water to the lower ends of said tubes, and a plurality of baffles extending between the bends of said tubes.

3. A heater comprising, in combination, a heating chamber having opposed side walls and end walls, two opposed walls being hollow to form water legs and extending substantially above the other walls, a hollow head casing secured between said last mentioned walls and over said other walls and communicating with the upper ends of said 50 water legs, a plurality of tortuous heating tubes disposed in said chamber, said tubes communicating with said head casing, means for supplying water to said tubes, and a plurality of baffles extending between the bends of said tubes, said baffles being freely mounted on said hollow walls for independent removal.

4. A heater comprising, in combination, an upright heating chamber, a head structure closing the top of said combustion cham-

ber, the interior of said structure constituting a water chamber, a part of the bottom wall of said head structure being raised to define a combustion chamber, a plurality of burners opening to said combustion chamber, a flue gas outlet at the lower end of said heating chamber, water legs along two sides of said heating chamber and communicating with said water chamber, and a series of tortuous heating tubes disposed in said combustion chamber and opening into said water chamber, and the lower ends of said water legs, and baffles disposed in the bends of said tubes.

5. A heater comprising, in combination, a heating chamber, a hollow head structure at the top of said heating chamber, the interior of said structure constituting a water chamber, a dome in the bottom wall of said head structure projecting into said water chamber, a plurality of burners in said dome, a flue gas outlet opening from said heating chamber, a series of heating tubes disposed in said heating chamber and opening into said water chamber at opposite sides of said dome, certain of said tubes discharging onto the top of said dome, and means for supplying water to said tubes.

6. A heater comprising, in combination, a heating chamber comprising two parallel walls having vertically spaced lateral grooves in their adjacent surfaces, a plurality of baffle plates slidably mounted in said grooves, said parallel walls having vertical grooves along the side edges, a plurality of vertical wall sections slidably mounted in said vertical grooves and confining the outer ends of said baffle plates, and a plurality of tubes extending along said baffle plates.

In testimony whereof we have hereunto affixed our signatures.
